UNITED STATES PATENT OFFICE.

ROBERT E. WILLIAMS AND WILLIAM A. TRAMMELL, OF DALLAS, TEXAS;
SAID TRAMMELL ASSIGNOR TO SAID WILLIAMS.

LAMP.

SPECIFICATION forming part of Letters Patent No. 340,965, dated April 27, 1886.

Application filed February 11, 1886; Serial No. 191,573. (No model.)

To all whom it may concern:

Be it known that we, ROBERT E. WILLIAMS and WILLIAM A. TRAMMELL, both residents of Dallas, in the county of Dallas and State of Texas, have invented certain new and useful 5 Improvements in Lamps; and we do hereby declare that the following is a full, clear, and exact description of the invention, which will enable others skilled in the art to which it applies to make and use the same, reference 10 being had to the accompanying drawings, which form a part of this specification, and in which—

Figure 1 is perspective view of our improved lamp, showing the reflector secured to throw the light directly out from the lamp. Fig. 2 is a similar view showing the reflector secured to throw the light from above. Fig. 3 is a vertical sectional view of the lamp and reflector, and Fig. 4 is a view of the reflector. 15

Similar letters of reference indicate corresponding parts in all the figures.

Our invention has relation to that class of lamps in which a reflector is secured to the lamp, having an aperture in its upper portion 25 for the passage of the chimney of the lamp, and in which the reflector may be adjusted to throw the light from the lamp in different directions without moving the lamp; and it consists in the improved construction and combination of parts of the same, as hereinafter 30 more fully described and claimed.

In the accompanying drawings, the letter A indicates the reservoir of the lamp, which 35 is formed by a bottom, B, pressed into the shape of a dish and having the top C secured with its edges to the edges of the bottom, the top being in this manner secured to the bottom or body of the reservoir, that the oil in 40 the lamp will not come in contact with the seams of the reservoir, avoiding the possibility of the lamp leaking through the seams. The top of the reservoir is provided with the usual burner, D, having the chimney E, both of 45 which may be of any suitable construction, and a cap, F, fits upon a short neck, G, through which the lamp may be filled. A strip, H, of sheet metal, is bent to form an upright portion, I, and an inclined portion, J, and is secured 50 to the top of the reservoir diametrically opposite to the burner, and the upright strip

is formed with a perforation or slot, K, by which it may be suspended from a nail or hook. The inclined portion of the strip and the top of the reservoir are provided with 55 thimble-shaped sockets L and M, the socket in the top of the reservoir being immediately to the rear of the burner, and a correspondingly-shaped plug or thimble, N, is secured to the lower edge of the reflector O, and fits 60 in either of the two sockets. Upon each side of the thimble the reflector is cut away, so as to form recesses T, which will fit around the collar when it is turned, so as to throw the light to either side of the lamp. 65

The reflector consists of a circular concave bottom, P, and a flaring ring, Q, which increases in width toward the upper portion, where it is formed with a circular aperture, R, for the passage of the lamp-chimney, and 70 the edge of the flange is corrugated or fluted, as shown at S, for the purpose of increasing the strength of the rim, and at the same time to add to its ornamental appearance.

It will be seen that when the thimble or 75 plug of the reflector is secured in the socket upon the inclined portion of the strip the reflector will stand at an inclined position to the flame of the burner and will reflect the light downward, and the light may be thrown in 80 different directions by the reflector, when the latter is turned with its plug in the socket, and the reflector may be changed from the socket in the strip to the socket in the top, when the reflector will throw the light straight 85 out from the burner, being capable of being turned, and thus to throw the light out in different directions in a horizontal plane, the cut-away portion of the lower edge of the flange allowing perfect freedom for the reflector. 90

The body of the reservoir, being pressed from one plate into its dish shape and having the edges of the top soldered to it at its upper edges, will not be liable to leak through the 95 seams as much as a reservoir having the body composed of several parts of sheet metal soldered or otherwise connected to each other.

Having thus described our invention, we claim and desire to secure by Letters Patent of 100 the United States—

1. The combination of a lamp-reservoir hav-

ing a burner and chimney near one edge and having a socket to the rear of the burner, a strip secured to the top of the reservoir diametrically opposite to the burner, and consisting of an upright portion having an aperture or slot and an inclined portion having a socket, and a reflector having a flaring flange provided in its wider upper portion with an aperture for the chimney, and having the lower portion of the flange cut away, and provided with a plug or thimble fitting in either of the sockets in the top or in the strip, as and for the purpose shown and set forth.

2. The combination of a lamp-reservoir having a vertical socket in its top near the burner,

and a flaring reflector having a vertical plug or thimble secured to its lower portion, said reflector being provided with a perforation in its upper portion and having a cut-away portion at each side of said plug at its lower portion, as shown and described.

In testimony that we claim the foregoing as our own we have hereunto affixed our signatures in presence of two witnesses.

ROBERT E. WILLIAMS.
WILLIAM A. TRAMMELL.
